METHOD OF FORMING SEPARABLE SNAP FASTENER STUDS

Walter I. Jones, Arlington, Mass., assignor to
United-Carr Fastener Corporation, Cambridge,
Mass., a corporation of Massachusetts

Application March 30, 1933, Serial No. 663,513

6 Claims. (Cl. 113—116)

My invention aims to provide improvements in separable snap fastener studs.

Reference is hereby made to the division of this application Serial No. 702,012, filed December 12, 1933.

In the drawing, which illustrates preferred embodiments of my invention:

Figure 1 is a plan view of one of my improved stud members;

10 Fig. 2 is a side elevation of the device shown in Fig. 1;

Fig. 3 is a plan view of the stud blank as it appears when cut from flat metal stock and before the socket-engaging members of the base 15 portions are bent into proper relation;

Fig. 4 is a plan view of my improved stud member partially formed; and

Fig. 5 is a plan, side elevation and edge view, respectively, of a modified form of my improved 20 stud member.

Referring to the particular embodiment of my invention illustrated by the drawing, I have shown a sheet metal snap fastener stud member cut from a flat strip of metal and having means, 25 which engage a cooperating socket member, bent up into position from a flat blank shown in Figs. 3 and 4 and portions of the blank bent toward each other to form a circular base with a substantially continuous periphery, as shown in Figure 1. This type of stud is very inexpensive to manufacture and is very suitable for use with upholstery installations because it has the advantage of a substantially continuous ring-like base, which is adapted to be easily inserted and 35 manipulated into engagement with upholstery or panelling and requires only three bending operations to complete it.

Briefly, the method of forming my improved stud member is to blank the skeleton of the stud 40 member from flat metal stock (Fig. 3), the said skeleton having a plurality of slits extending from one side thereof, thereafter to bend the inner portions of the blank defined by said slits to a substantially right angle to the plane of the blank 45 to form the socket-engaging portions and then to bend outer portions in the plane of the blank to form a circular base having a substantially continuous periphery.

The stud member illustrated has a base portion 1 having slits 2, 2 and 3 to define the socket-engaging portions 4, 4 and arms 5, 5. These arms 5, 5 connect the socket-engaging portions 4, 4 with the base portion 1, as shown in Figs. 1 and 3. After the blank has been cut from the 55 metal strip, the projections or socket-engaging

portions 4, 4 are bent upwardly (as shown in Fig. 4) to a substantially right angle with the plane of the base portion 1. The projections 4, 4 are located in different planes so they may overlap (Figs. 1, 2 and 4) and the outer edges 6, 6 are so arranged that they cooperate to provide a stud head portion 7 and a neck portion 8. The edges 6, 6 diverge from the plane of the base to the shoulders 9, 9 and then converge. The converging head portion 7 is easily guided into an aperture and the diverging or neck portion 8 readily adjusts itself to various thicknesses of metal when entered through an aperture because of the length of the neck.

The final operation in the manufacture of the stud member is to bend the portions 10, 10 toward each other, as shown partly in Fig. 4 and in the completed member, they being separated only by a narrow slit 11 which may add flexibility to the base. The completed stud member has to all intents and purposes a continuous metal periphery which is one important feature of my invention.

It should be noted that the projections 4, 4 are rigid throughout the length of each as far as any tendency to bend toward or away from each other is concerned. However, when it is desired to engage the stud member with a wall of a stud-receiving aperture of fixed dimensions, the portions 4, 4, are permitted to have a scissors like action, both being adapted to move toward each other, thereby reducing sufficiently the distance between the shoulders 9, 9 to allow the projections to enter a socket or stud-receiving aperture, whereupon the projections spring outwardly and the edges 6, 6, pressing against the walls of the adjacent aperture, hold the stud firmly in position with respect to said aperture. The yieldable projections (moving in the above-described scissors-like motion, thereby to make engagement with a cooperating fastener socket) are adapted to do so by the resiliency of the base portion 1 and the arms 5, 5. The shape and arrangement of the arm portions 5, 5 may vary widely according to the size and shape of the base, but the arrangement illustrated is particularly satisfactory because the flexing of the base is not concentrated in any one spot but is so distributed as to prevent setting of the projections 4, 4 when squeezed together.

A modified form of a stud member is shown in Fig. 5. The principle is the same as in the fastener just described, but the yieldable projections, instead of being arranged as described, are set substantially in alignment, the yieldable projections

being shaped to move toward and away from each other in the same plane.

The side elevation of Fig. 5 illustrates a projection 14 having an outer edge 15 extending upwardly and outwardly to a shoulder 16 and a continuation of the said edge (indicated at 17) extending upwardly and inwardly and thereafter downwardly and outwardly to form the outer edge of the head 18. The projection 14 has an inner edge 19 cut away, thereby to permit the other projection 20 to move toward and nest with the projection 14 during fastening engagement with a cooperating fastener socket. The projection 20 has an outer edge 21 which extends upwardly and outwardly to the shoulder 22 and a continuation of the said edge (indicated at 23) extending upwardly and inwardly so that the outer edges of the two projections form a substantially continuous surface on the head portions whereby the stud may easily be inserted into a socket without catching.

The result of my invention is a strong, durable stud member which has a relatively stiff spring action adapted to hold the part to which the stud is attached, for example, upholstery, panelling, etc., and also has a circular base with a substantially continuous metal periphery which allows easy insertion beneath the above-mentioned upholstery or panelling.

I am aware that stud members cut and bent from sheet metal are old in a broad sense; however, I do not know of any prior stud which is formed similar to my improved studs or which has the same action or arrangement of the elements thereof.

While I have shown and described preferred embodiments of my invention, it will be understood that I do not wish to be limited thereto, the scope of my invention being best defined in the following claims.

1. The method of forming a one-piece snap fastener stud member having a relatively flat base and yieldable socket-engaging means extending from said base which comprises forming a blank 45 of the stud member from stock to form a U-shaped base and socket-engaging means inside the U-shaped base, thereafter bending the yieldable socket-engaging means of the blank to a substantially right angle to the plane of the blank 50 and then bending the end portions of the said U-shaped base in the plane thereof to form a base having a substantially continuous periphery.

2. The method of forming a one-piece sheet metal snap fastener stud member having a relatively flat base and yieldable socket-engaging means extending from said base which comprises forming a blank of the stud member from sheet metal stock, thereafter bending the yieldable socket-engaging means of the blank to a substantially right angle to the plane of the blank

and then bending portions of the said blank toward each other in the plane thereof to form a base having a substantially continuous periphery.

3. The method of forming a one-piece sheet metal snap fastener stud member having a relatively flat base and yieldable socket-engaging means extending from said base from a blank having a plurality of slits therein which comprises forming a blank of the stud member from metal stock, thereafter bending portions of said blank defined by said slits to a substantially right angle to the plane of the blank, said portions forming the said yieldable socket-engaging means, and thereafter bending other portions of said blank in the plane thereof to form a base having a substantially continuous periphery.

4. The method of forming a one-piece sheet metal snap fastener stud member having a relatively flat base and yieldable socket-engaging means extending from said base from a blank having a plurality of slits extending inwardly from one side thereof, said slits defining the yieldable socket-engaging means and base of said stud member, which comprises forming a blank of the stud member from metal stock, bending portions of said blank to a substantially right angle to the plane of said blank, said portions forming a yieldable socket-engaging means, and thereafter bending other portions of said blank in the plane thereof to form a base having a substantially continuous metal periphery.

5. The method of forming a one-piece sheet metal snap fastener stud member having a relatively flat base, yieldable socket-engaging means extending from said base from a blank having a plurality of slits extending inwardly from one side thereof, said slits defining the yieldable socket-engaging means and base of said stud member which comprises forming a blank of the stud member from metal stock, bending the inner portions of said blank defined by said slits to a substantially right angle to the plane of the blank, said inner portions forming said yieldable socket-engaging means, and thereafter bending the outer portions of said blank and in the plane thereof to form a base having a substantially continuous metal periphery.

6. The method of forming a one-piece snap fastener stud member having a relatively flat base and yieldable socket-engaging means extending from said base which comprises forming a blank of the stud member from stock, thereafter bending the yieldable socket-engaging means of the blank to a substantially right angle to the plane of the blank and substantially on a line transverse the said blank and then bending portions of the said blank in the plane thereof to form a base having a substantially continuous periphery.
